UNITED STATES PATENT OFFICE.

WALTER T. GORTON, OF THE UNITED STATES ARMY.

OPERATING SLIDE AND HANDLE FOR MACHINE GUNS.

Application filed July 12, 1922. Serial No. 574,555.

(FILED UNDER THE ACT OF MARCH 3, 1883, 22 STAT. L., 625.)

To all whom it may concern:

Be it known that I, WALTER T. GORTON, captain Ordnance Department, United States Army, a citizen of the United States, 5 stationed at Springfield Armory, Springfield, Mass., have invented an Improvement in Operating Slides and Handles for Machine Guns, of which the following is a specification.

10 The invention described herein may be used by the Government, or any of its officers or employees in prosecution of work for the Government, or by any other person in the United States, without payment to me of any royalty thereon, in accordance with the act of March 3, 1883.

15 The subject of this invention is an operating slide and handle for machine guns and is designed especially for machine guns to 20 be used in aircraft.

25 The Browning aircraft machine gun is used as a fixed synchronized gun and is, therefore, operated by the pilot, who has only one hand free for operating and firing the gun. For this reason some means for loading and unloading the gun, and for movement of its working parts by hand are necessary.

30 My invention is designed to provide means whereby, with the use of one hand, the gun may be properly operated and functioned.

35 With these and other objects in view my invention resides in the novel arrangement and combination of parts and in the details of construction hereinafter described and claimed, it being understood that changes in the precise embodiment of the invention herein disclosed may be made within the 40 scope of what is claimed without departing from the spirit of the invention.

45 Practical embodiments of the invention are illustrated in the accompanying drawings, wherein:

Fig. 1 is a view in side elevation of the device showing the same attached to the side plate of a machine gun;

Fig. 2 is a similar view of the operating slide and handle, detached;

Fig. 3 is a view in side elevation of a modified form of the slide and handle, showing the same attached to a machine gun and

Fig. 4 is a plan view of the same.

A side plate of the machine gun is indi-

cated by the numeral 10, formed with the 55 usual longitudinally extending slot 11 in which the operating handle or stud 12 of the bolt reciprocates as the bolt is moved back and forth in the operation of the gun.

Secured to the side plate rearwardly of the slot, conveniently by rivets, is a guide bar 13 which may be formed with a forwardly projecting rest 14 affording a greater bearing surface, and at the rear end of the plate is likewise secured a second guide bar 15 having a cut-out portion 16 extending below the surface of the rearwardly extending rest 17. An arm or lug 18 projects rearwardly from the upper end of the guide 15 and has an aperture for the reception of a plunger 19, urged downwardly conveniently by coil spring 20.

Mounted for sliding movement in the guides is a slide bar 21 cut away for a distance adjacent its forward end to provide a hook 22 which engages the forward side of the stud 12, and to provide clearance for the stud. The lower edge of the slide bar is provided with spaced apart notches 23 and 24 of sufficient length to engage over the rest 17, for a purpose hereinafter set forth, but normally positioned out of engagement with such rest. A rivet or pin 25 is secured in the bar 21 in position to normally contact the rear face of the guide 15 and so limit the forward movement of the bar.

The rear end of the bar is preferably angularly disposed as at 26 to form a handle through means of which the bar may be readily manipulated. In the modified form shown in Figs. 3 and 4 the operation of the bar is exactly the same as that of the bar hereinabove described but the structure is slightly different in that the slot 11' in which the breech bolt handle 12' operates is nearer the rearward end of the side plate 10' so that the slot, in this instance, is positioned between the guide bars 13' and 15' respectively and these guide bars have been modified by eliminating the rest 14 from the forward guide bar and the rearwardly extending portion from the rear guide bar.

The slide bar itself is of slightly different form having an elongated end 28 which reciprocates in the forward guide bar 13' and being provided with a detachable finger 22' adapted to engage the rear face of the forward guide bar to limit the forward move-

ment of the slide and to contact the forward surface of the stud 12' to draw the same rearwardly when required. This slide bar 21' is likewise provided with spaced apart notches 23' and 24' which are adapted to receive the lower edge of the guide bar 15'. When this bar is to be removed from one side of the gun and placed upon the opposite side the finger 22' is detached by removing the screws or pins which hold it in place, the bar withdrawn from the guides and inserted in the guides on the opposite side plate of the gun and the finger replaced in position on the opposite side of the slide.

15 In the normal automatic operation of the gun the handle and slide stays in the forward position as shown in Figs. 1 and 3, in which position the bolt handle or stud 12 or 12' operates freely in the rear of the hook 22 or finger 22'. If it is desired to open the breech mechanism of the gun the handle and slide is pulled straight to the rear, and may be locked in its rearmost position by slight downward pressure which causes engagement in one instance of the lug 17 of the rear guide in the recess 23 of the slide and in the other instance the lower edge of the rear guide 15' in the recess 23' of the slide. This locks the bolt in its fully recoiled position, which is frequently of considerable assistance in reduction of stoppages. The slide is steadied in its retracted position by the action of the spring pressed plunger 19 or 19' which engages its upper surface and retains it in its pressed down position. On pressing the slide upward it is released and then carried forwardly by the bolt under the influence of its driving spring. The stop 40 25 in one instance and the finger 22' in the other instance prevents the slide from moving forwardly too far, and when in its forward position it is held by the seating of the plunger in a depression 27 or 27' formed 45 in the upper surface of the slide.

To effect unloading of the chamber of the gun, the handle is grasped and the slide 21 or 21' drawn completely to the rear, then allowed to move forward until the rear notch 24 or 24', as the case may be, in the slide is engaged by the lug 17 or lower portion of guide 15', then once more drawn completely to the rear and finally allowed to spring forward. On the first of these rearward movements a cartridge is extracted from the belt and, on the subsequent forward movement is partially inserted in the chamber. However, the rear notch in the slide is so positioned that when the lug of the rear guide is engaged in it, the next cartridge in the belt is not gripped by the extractor, consequently, on the second rear-

ward movement of the slide no new cartridge is taken from the belt, and the live round, which had been previously partially inserted in the chamber is extracted and ejected, leaving the gun unloaded.

65 The slide is so proportioned that it may be removed from its guides by simply pulling it straight to the rear, after the bolt handle or stud 12 has been removed or in the case of the modified form after the finger 22' has been removed.

I claim:

1. An operating handle and slide for a machine gun, having a bolt stud, including guides secured to the side of the gun, a lug formed on one of said guides, said slide reciprocable in the guides, a hook at the forward end of the slide normally engaging the forward surface of the stud, said slide provided with spaced apart notches in its lower edge adapted to engage over the lug and positioned to lock it in its rearmost position or in a position just prior to gripping of a cartridge in the cartridge belt by the extractor of the gun, means for limiting the forward movement of the slide, means for holding the slide either in normal position or in position with the notches in engagement with the lug and a handle formed on the slide.

2. The combination with a machine gun having a bolt stud of guides secured to the side of the gun, a slide reciprocable in the guides and engaging the stud operable to move the stud to its rearmost position, and means for detaining the slide to releasably hold the stud in such rearmost position or to lock the stud in a position just prior to the gripping of a cartridge in the cartridge belt by the extractor of the gun.

3. The combination with a machine gun having a bolt stud of guides secured to each side of the gun, a slide formed for selective engagement with the guides of either side of the gun reciprocable in the guides and engageable with the stud and operable to move the stud to its rearmost position, and means for detaining the slide to releasably hold the stud in such rearmost position or to lock the stud in a position just prior to the gripping of a cartridge in the cartridge belt by the extractor of the gun.

4. The combination with an automatic gun having a breech bolt, of a slide attached to the gun and connected to the bolt and operable to move the bolt to its rearmost position and means for detaining the slide to releasably hold the bolt in such rearmost position or to lock the bolt in a position just prior to the gripping of a cartridge in the cartridge belt by the extractor of the gun.

WALTER T. GORTON
